F. W. LAWYER

DISTRIBUTOR ATTACHMENT FOR OIL CANS

Filed June 10, 1927

Levettaius,

WITNESS:

*Frank W. Lawyer,
INVENTOR*

Victor J. Evans

ATTORNEY

UNITED STATES PATENT OFFICE.

FRANK W. LAWYER, OF PLACERVILLE, CALIFORNIA.

DISTRIBUTOR ATTACHMENT FOR OIL CANS.

Application filed June 10, 1927. Serial No. 197,919.

This invention contemplates the provision of a novel construction of oil can primarily designed for wiping carpenter's saws or any other surface with a lubricant, although it 5 can be used for distributing a cleaning agent over automobile surfaces, furniture or the like in a manner whereby the liquid is evenly or uniformly distributed.

The nature and advantages of the invention will be better understood when the following detail description is read in connection with the accompanying drawing, the invention residing in the construction, combination and arrangement of parts as claimed.

15 In the drawing forming part of this application like numerals of reference indicate similar parts in the several views and wherein:

Figure 1 is a view in elevation of the invention.

Figure 2 is a vertical sectional view therethrough.

Figure 3 is a detail view of the wiping element.

20 Figure 4 is a view of the perforated disk.

Figure 5 is a sectional view through one of the washers.

The device forming the subject matter of the present invention comprises a receptacle 30 10 adapted to contain a liquid, the receptacle being provided with a flange 11 at the mouth thereof. The receptacle is interiorly threaded as at 12, and may of course vary in size and configuration without departing from the inventive idea.

35 Threaded into the mouth of the receptacle is a substantially tubular shaped member 13 including an outwardly bulged intermediate portion 14 arranged above the flange 11. Seated within this bulged portion is a perforated disk 15 constituting a support for the wiping element 16, which as clearly illustrated in Figure 2 is arranged within the upper portion of the tubular member 13. The 40 wiping element may be formed from any suitable soft absorbent material, such as felt, and preferably rolled as illustrated in Figure

3, the said element projecting an appreciable distance beyond the adjacent end of the tubular member 13.

50 This element is normally covered and protected by a cap 17, which is preferably threaded on the adjacent portion of the tubular member 13 as illustrated in Figure 2. This cap is also provided with a flange 18 55 similar to the flange 11, while interposed between each of these flanges and the bulged portion 14 of the tubular member is a washer or gasket 19. The cap is also provided with a ring 20 pivoted so as to lie parallel with the 60 top of the cap, and which ring may vary in size.

65 In practice, the receptacle 10 is filled with liquid, and when it is desired to use the device, it is only necessary to remove the cap 17 and invert the receptacle 10. The liquid passes through the perforations in the disk 15, thereby moistening the wiping element 16, the latter being used to uniformly distribute the liquid over the surface to be 70 wiped.

75 While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

80 A device of the character described comprising a receptacle adapted to contain a liquid, a hollow tubular member threaded in and projecting from the open end of the receptacle, a perforated disk arranged within the tubular member, a wiping element comprising a coil of felt partly arranged within the tubular member and reposing upon said disk, and a cap normally covering said wiping element and removably associated with said 85 tubular member.

89 In testimony whereof I affix my signature.

FRANK W. LAWYER.
